J. BERG & L. W. GOLDER,
ELECTRIC HEATER,
APPLICATION FILED DEC. 4, 1916.

1,258,641.

Patented Mar. 12, 1918.

Fig. 1.

UNITED STATES PATENT OFFICE.

JOHN BERG AND LLOYD W. GOLDER, OF CHICAGO, ILLINOIS, ASSIGNEES TO METAL SPECIALTIES MANUFACTURING COMPANY, OF CHICAGO, ILLINOIS, A CORPORATION OF ILLINOIS.

ELECTRIC HEATER.

1,258,641.

Specification of Letters Patent. Patented Mar. 12, 1918.

Application filed December 4, 1916. Serial No. 134,983.

To all whom it may concern:

Be it known that we, JOHN BERG and LLOYD W. GOLDER, citizens of the United States, residing at Chicago, in the county 5 of Cook and State of Illinois, have invented a new and useful Improvement in Electric Heaters, of which the following is a specification.

This invention relates particularly to 10 small portable electric heaters which may be usefully employed in various situations, as, for instance, for the purpose of keeping the engine and radiator of an automobile warm in an unheated garage.

15 The primary object of the present invention is to provide a heater of the character indicated which can be manufactured at moderate cost, which shall be of such durable character as to withstand the rather hard 20 usage to which it is liable to be subjected, and which can be thrown into contact with metal surfaces without danger of being short-circuited or otherwise injured.

A heater of the character referred to may, 25 for instance, be thrown under the hood of an automobile, and a blanket may then be placed over the hood, so that but small electric energy will be required to provide the requisite heat to keep the engine moderately 30 warm and prevent freezing of the water in the radiator.

A further object of the invention is to provide for effective radiation of the heat developed by the electric current, in order 35 that the electrical device will not itself become overheated, and the heat developed will be usefully employed in maintaining the desired temperature beneath the hood of the automobile.

40 The invention is illustrated in its preferred embodiment in the accompanying drawings, in which—

Figure 1 represents a longitudinal sectional view of an electric heater constructed 45 in accordance with our invention, the section being taken at line 1 of Fig. 2; Fig. 2, a transverse sectional view taken at line 2 of Fig. 1; Fig. 3, an end elevational view of the pair of insulating cores employed and 50 the windings and connections thereof; Fig. 4, an inner view of the casing-cap shown at the left-hand end of Fig. 1, the view showing brokenly an internal insulating sheet 55 employed within the cap; Fig. 5, an enlarged sectional view of one of the cores, 60 showing the windings thereon; Fig. 6, a broken vertical sectional view taken as indicated at line 6 of Fig. 4, and showing a detail of the manner in which the foraminous shell employed as a casing is connected with and supported by the end cap; and Fig. 7, a fragmentary view of a relatively soft asbestos core employed in connection with the relatively hard asbestos core, said core serving as a spacer of the convolutions 65 of the naked wire windings by reason of the fact that the core is readily deformed or indented by the wire when it is wound tightly upon the core.

In the illustration given, A represents a 70 foraminous metal shell which is fitted with metal caps A¹, A², thus providing a perforate casing for the heater; B, B¹, a pair of cores of insulating material connected at their ends with the end caps of the casing 75 or shell; and C, C¹, bare wire windings on said cores. Each of the cores B, B¹, preferably comprises an asbestos tube 1 of relatively large diameter and an asbestos tube 2 of relatively small diameter fitted snugly 80 therein and having projecting extremities, which thus afford reduced extremities for the cores. These asbestos tubes are comparatively hard and firm, being preferably formed of very tightly wound asbestos 85 paper, the plies of paper being united by a binder, if desired. Thus, the cores are provided with comparatively hard outer surfaces upon which the bare wire forming the resistance element is tightly wound. Preparatory to winding the wire on the core, the core is preparatorily provided with longitudinally-disposed strips or cords 3 of 90 comparatively soft insulating material. An asbestos cord formed of long and somewhat 95 loosely twisted or woven asbestos fiber serves the purpose admirably. A number of these cords may be preparatorily secured to the core in any desired manner, after which the wire may be wound tightly upon the core, 100 the result being that the convolutions of the wire indent or deform the longitudinal strips 3 so that the convolutions are thereby effectually separated from each other, notwithstanding the fact that the surface of the 105 asbestos core proper is so firm or compara-

tively hard that the convolutions of the wire might slip into contact with each other, were it not for the relatively soft longitudinal spacers employed.

- 5 In constructing the device, each core is wound separately, and the wire is secured near its extremities to pins or screws 4 which are entered or driven into the cores near the ends thereof. The reduced ends of the cores 10 are fitted at one end of the device with binding rings 5 and 6, and are fitted at the other end of the device with binding rings 7 and 8. The binding rings 5 and 6 are in the form of clamping rings which are fitted 15 with clamping screws 9, each of which is equipped with a pair of nuts as shown. The adjacent extremities of the wires pass through the clamping screws 9 and are secured to said clamping screws by being 20 clamped between the nuts thereof. One extremity of each of the clamping rings 5 and 6 is provided, respectively, with an extension or arm 5^a and 6^a which are united by a screw-bolt 10.
- 25 The opposite ends of the wires forming the windings are connected with the binding rings 7 and 8, which are in the form of clamping rings fitted with clamping screws 11 which are equipped with pairs of nuts 30 which serve to clamp the extremities of conductors 12, which enter the shell through an insulating ferrule 13 which extends through the end cap A¹.

The casing is preferably of flattened or 35 somewhat oval cross-section, as shown in Fig. 2. The shell A may be formed from a thin foraminous sheet of metal which is bent or curved into the desired form, the longitudinal edge portions of the plate being overlapped, as indicated at 14. The opposite sides of the shell are united by a central post 15, one end of which is riveted to the overlapped edge-portion and the other end of which is riveted to the opposite wall of the shell. The post or transverse support 15 is shouldered, so that the opposite walls of the shell are secured in properly spaced relation.

The end caps A¹ and A² are provided 50 with flanges 16 which fit over the ends of the shell; and the end caps are also provided with inwardly struck lugs 17 which are disposed beneath the end portions of the walls of the shell in alignment with the post 15, so that the broad sides of the shell are supported and spaced at their ends by the lugs 17 in addition to being supported and spaced at a central point by the post 15. The detail of the end caps referred to 55 60 will be understood from Figs. 4 and 6. The ferrule 13 extends through a central perforation in the end cap A¹ and has an external flange which bears against the outer surface of the end cap. The ferrule also extends through a pronged spring-washer

18 disposed adjacent the inner face of the cap A¹, which thus serves as a retainer for the ferrule.

The cores B, B¹ are supported between the end caps by means of bolts 19 which extend through the end caps and cores and clamp the end caps against the cores and also against the ends of the shell A. Insulating sheets 20 are interposed between the ends of the cores and the inner surfaces 75 of the end caps. The sheets 20 may be of asbestos, if desired. These insulating sheets serve to prevent the electrical connections from coming in contact with the ends of the metal casing. The cores and their supporting bolts are disposed on opposite sides of the intermediate post 15.

In the use of the device, the electric current enters through one of the conductors 12, passes through the winding on one of 85 the cores, then through the connecting rings 5 and 6 to the winding on the other core, and finally back through the other conductor 12 to the source of electrical supply.

A structure of the character described is 90 durable and may be thrown under the hood of an automobile without injury to the device and without danger of short-circuiting. It is constructed to withstand the rough usage to which it is subjected in and about 95 a garage. The structure lends itself to convenience in the manufacture of the parts and in the assembling thereof, so that the device can be cheaply manufactured.

The foregoing detailed description has 100 been given for clearance of understanding only, and no unnecessary limitation should be understood therefrom, but the appended claims should be construed as broadly as 105 permissible in view of the prior art.

What we claim as new and desire to secure by Letters Patent is—

1. In an electric heater of the character set forth, a core of insulating material having a comparatively hard surface, a relatively soft insulating strip on said core, and a naked wire winding on said core having its convolutions indenting said soft insulating strip which thus serves as a spacer for 110 said convolutions.

2. In an electric heater of the character set forth, a pair of cores of insulating material having comparatively hard surfaces, relatively soft longitudinal insulating strips on said cores, naked wire windings on said 115 cores having their convolutions indenting said longitudinal insulating strips and spaced thereby, electrical connections between said wire windings at one end of said cores, and conductors connected with said 120 windings at the opposite end of said cores.

3. In an electric heater, the combination of a foraminous metal shell, a pair of end caps therefor, insulating sheets adjacent the inner surfaces of said end caps, a pair of 125 130

cores having reduced extremities disposed adjacent said insulating sheets, binding rings on the reduced extremities of said cores, the binding rings at one end of the device being connected together, wire windings on said cores connected with said binding rings, conductors connected with the binding rings which are not joined together, said conductors extending through the adjacent end cap of the heater, and bolts extending through said end caps and cores and serving to secure the end caps in place and support said cores. 10

JOHN BERG.
LLOYD W. GOLDER.
